UNITED STATES PATENT OFFICE

2,672,073

ROTATABLE SHUTTER ARRANGEMENT FOR
CINEMATOGRAPHIC CAMERAS

Jacques Bolsey, New York, N. Y.

Application January 17, 1950, Serial No. 139,000

1 Claim. (Cl. 88—19.3)

1

My present application is a continuation-in-part of my U. S. patent application Serial No. 775,798, filed on September 24, 1947, now abandoned. Said U. S. patent application Serial No. 775,798 is a continuation-in-part of my U. S. patent application Serial No. 534,623, filed May 8, 1944, now abandoned. Said U. S. patent application Serial No. 534,623 is a continuation-in-part of my U. S. patent application Serial No. 340,465, filed June 14, 1940, now abandoned.

My present invention relates to rotatable shutter arrangements for cinematographic cameras.

It is the object of my present invention to provide means for adjusting the position of the shutter blades for a rotatable shutter during rotation of the same.

The novel features which I consider as characteristic for the invention are set forth in particular in the appended claim. The invention itself, however, both as to its construction and its mode of operation will be best understood from the following description of a specific embodiment when read in connection with the accompanying drawing showing a side view of such embodiment partly in cross section.

The shutter arrangement, according to my present invention, is mainly employed in cinematographic cameras where the shutter rotates continuously during taking of pictures. In the embodiment shown in the drawing, the shutter is rotated by means of a pinion 60 which drives the pinion 61 which is mounted on the inner shaft 85. On this inner shaft 85 is secured a sleeve 99 which carries the fixed blade 88 of the shutter. The blade 89 of the shutter is movable relative to the fixed blade 88 so as to adjust the shutter opening. For this purpose this movable blade 89 is secured to the tubular shaft 100 which is freely slidably mounted on the sleeve 98a which in turn is freely slidably and rotatably carried by the inner shaft 85. In this arrangement the tubular shaft 100 is provided with a straight longitudinal slot 104 into which projects the pin 103 mounted on sleeve 98a. Furthermore, the inner shaft 85 is provided with a helical groove 102 which is engaged by the inwardly projecting radial pin 101 mounted on sleeve 98a.

As shown, spring 105 is arranged within the tubular shaft 100 permanently tending to push the sleeve 98a in outward direction.

As clearly shown in the drawing, sleeve 98a is engaged by the free end 83a of the lever 82 which is connected by the removable stud 82b and spring 98 to the adjusting lever arm 78 pivoted at 79. The lever 78 can be turned together with the lever 82 about pivot 79 by means of the roller 78a mounted on lever 78. For this purpose the heart-shaped cam 77 is provided, turning of which results in corresponding turning of the levers 78 and 82.

Such turning of lever 82 will result in in-

ward pushing of the sleeve 98a and turning of the movable blade 89 relative to the fixed blade 88, if desired. It is evident that by the sliding engagement between the free lever end 83a and the sleeve 98a it is possible to adjust, by the above described arrangement, the relative position of shutter blades 89 and 88 during operation of the same.

What I claim is:

10 1 Shutter arrangement for a cinematographic camera comprising in combination, a rotatable outer tubular shaft provided with a slot extending parallel to the axis of said shaft over part of the length thereof; a shutter blade carried by said rotatable outer tubular shaft; a rotatable inner shaft provided with a helical groove in its surface and arranged within said rotatable outer tubular shaft and having projecting end portions projecting at both ends beyond the ends of said rotatable outer tubular shaft; another shutter blade carried by one projecting end portion of said rotatable inner shaft and cooperating with said shutter blade carried by said rotatable outer tubular shaft; a pinion firmly secured to said one end portion of said rotatable inner shaft coaxially with the same; gear means for rotating said pinion; a sleeve member mounted on the other projecting end portion of said rotatable inner shaft turnably and slidably with respect to the latter; an inwardly projecting projection on said sleeve reaching into said helical groove in said rotatable inner shaft; an outwardly projecting projection on said sleeve reaching into said slot in said rotatable outer tubular shaft; spring means mounted between one of said shafts and said sleeve permanently forcing the same in outward direction; and adjusting means abutting against the outer end of said sleeve and permanently forcing the same in inward direction so as to move said sleeve and thereby adjust the relative angular position of said shafts and of the shutter blades carried by the same.

JACQUES BOLSEY.
